UNITED STATES PATENT OFFICE.

REINHOLD HERMAN, OF CRAFTON, PENNSYLVANIA.

CIRCUIT-CONTROLLER.

SPECIFICATION forming part of Letters Patent No. 699,952, dated May 13, 1902.

Application filed October 7, 1901. Serial No. 77,762. (No model.)

To all whom it may concern:

Be it known that I, REINHOLD HERMAN, a citizen of the United States of America, residing at Crafton, in the county of Allegheny 5 and State of Pennsylvania, have invented certain new and useful Improvements in Circuit-Controllers, of which the following is a specification, reference being had therein to the accompanying drawings.

10 This invention relates to certain new and useful improvements in circuit-controllers such as are employed in connection with electrically-operated signal devices, the main object of the invention being to construct a 15 circuit-controller for controlling a multiple number or series of circuits.

While I will herein describe and illustrate the device as employed in connection with a signal mechanism, yet the device can be 20 readily employed in any connection where a rotary shaft is obtainable and wherein it is desired to use a controller for timing a series of movements of shorter or longer duration.

In describing the invention in detail reference is had to the accompanying drawings, forming a part of this specification, and wherein like numerals of reference indicate corresponding parts throughout the several views, in which—

30 Figure 1 is a side elevation of my improved circuit-controller, showing the same secured in position on one of the standards or uprights of a signal mechanism, the standard or upright being partly broken away. Fig. 35 2 is a top plan view thereof. Fig. 3 is a transverse vertical sectional view taken on the line 3 3 of Fig. 1. Fig. 4 is a like view taken on the line 4 4 of Fig. 1. Fig. 5 is a transverse vertical sectional view through one 40 of the shafts for the contact fingers or blades, taken on the line 5 5 of Fig. 6. Fig. 6 is a central vertical sectional view of one of the sleeves or collars which carry the contact fingers or blades, showing the latter in position and also showing a part of the shaft. Fig. 7 is a detail side and face view of one of the sleeves or collars that carry the contact fingers or blades.

In the accompanying illustration of my invention only that part of the framework and other parts of a signal mechanism are shown

as is necessary to give a clear understanding of the device. As is well known in signaling a signal mechanism is employed to shift the signal to different positions, and in 55 some of these devices—for instance, as shown in my Patent No. 683,397—a rotating drive-shaft is journaled in the framework of the signal mechanism, and mounted on this drive-shaft is a circuit-controller for effecting the 60 desired circuits to shift the signal to its different positions. In the present device I aim to provide means whereby the contact fingers or blades may be adjusted so as to complete one or more circuits at predetermined periods, 65 and in the drawings 1 indicates a part of one of the standards or uprights of the signal-mechanism frame. A form of these standards and signal mechanism is shown in my patent before referred to, and journaled in 70 the standards is the drive-shaft 2.

The improved form of circuit-controller herein shown is adapted not only to be employed with a signal mechanism especially constructed therefor, but also to be attached 75 to any mechanism having a rotating drive-shaft. In the present illustration I show the same attached to a standard or upright not specially constructed therefor. I accomplish this by tubular studs or bushings 3, to which 80 the segment-shaped supporting-plate 4 is secured by bolts 5. The circuit-controller mechanism is adapted to be mounted on the outer face of the standard or upright 1, and on the end of the drive-shaft 2 that projects through 85 the standard 1 I mount a sleeve 6, that may be held against rotation independently of the shaft by means of a tap-screw 7 or other suitable means. This sleeve is preferably provided intermediate of its ends with an annular flange 8, and mounted on the sleeve on each side of the flange is a securing-collar 9, composed of insulating material, in which the contact segments or plates 10 are held. The securing-collars are peripherally grooved and 90 may be fastened to the sleeve 6 by set-screws 11, as shown, and the contact segments or blades 10 may be held in the collars 9 by screws 12, as shown, or in any other suitable manner. The ends of the contact segments 100 or blades 10 are made V shape in cross-section or with a knife-edge 14, so that they

- will readily enter between the contact-fingers without danger of the latter striking against the end of the segment and interrupting the movement thereof.
- 5 It will be observed that by slackening screw 7 sleeve 6 may be revolved on shaft 2 and adjusted to any desired position in order that the time of contact of the blades 10 with the spring contact-fingers may be varied.
- 10 The segment-shaped supporting-plate 4 carries one or more studs from which the contact fingers or blades for engagement with the plates 10 are suspended and with which studs circuit is made to various parts of the mechanism to control and give the desired movements of the signal. In the present illustration I have shown three of these studs, (indicated by the numerals 14 15 16,) each substantially identical in construction. Each
- 15 stud has an integral enlargement or collar 17, having an aperture 18 for one of the circuit-wires (not shown) and a set-screw 19 for securing the wire in position. As the circuit to the contact fingers or blades carried by the
- 20 studs are not identical with each stud I will describe each stud separately. The stud 14 projects through plate 4 and is secured by a lock-nut 20. An insulating-sleeve 21 is placed on the stud to prevent contact of the plate 4 therewith, and the plate 4 is also insulated from the nut 20 and collar 17 by insulating-washers 22. Mounted on the stud 14 on the other side of the collar 17 are two adjustable collars 23, which carry the contact fingers or
- 25 blades 24. These contact fingers or blades are apertured, so that the stud may be inserted therethrough, and the collars 23 are provided in opposite faces with recesses 25, into which the fingers fit neatly. The collars 23 are
- 30 spaced apart by washers 26, placed on the stud, and they are rigidly secured on the stud by a washer 27 and nut 28. The stud 15 is identical in construction with the stud 14, is insulated in the same manner from the plate 4, secured in a like manner, and the contact-fingers are also held on the stud by a washer and nut, as in the construction described in connection with the stud 14, and the same numerals have therefore been applied to these
- 35 parts. This stud also carries two pair or sets of contact-fingers 29 30, the former secured to a collar 23 of the same construction as the collars on stud 14 and the latter secured to a collar 31, that is recessed or countersunk
- 40 on opposite faces in the same manner as the collars 23, but has a bore sufficiently large to fit over an insulating-sleeve 32, mounted on the stud, the fingers 30 being also insulated from the stud. The collar 31 and fingers 30
- 45 are also insulated from the collar 23 and fingers 29 by an insulating-washer 33, the circuit being completed to the fingers 30 over a circuit-wire (not shown) which is attached to a binding-post 34, carried by the collar 31.
- 50 The stud 16 has the integral collar 17 with aperture 18 for circuit-wire and is held in the plate 4 and insulated therefrom in the
- same manner as the studs 14 and 15. Mounted on this stud 16 is a pair of peripherally-grooved collars 34, which are also countersunk or recessed on both side faces to receive the contact-fingers 35, these fingers being held in position on the collars by washers 36 and screws 37, as shown. Each of the collars 34 is provided with a slot 38, and a stud 70 or screw 39 extends through this slot into the shaft 16, while on either side of this stud or screw 39 there is secured in the flanges of the collar a pin 40 to limit the oscillating movement of the collars 34 and their fingers 75 35. The collars 34 are spaced apart on the stud by washers 41, placed therebetween, and are held in position on the stud by the pins or screws 39 in lieu of the nut 28, as with the other two studs, the washer 42, which binds 80 the outside finger 35 in place, being secured by the small screws 37. All the fingers or blades may be made oscillating, as is shown for the fingers 35, providing there would be a heavy charge of current passed over them 85 in order to procure a quick and long break between segments and fingers. This quick break of the fingers mounted, as is shown for the fingers 35, is occasioned by reason of the fingers being pivoted, and when the limit of 90 their contact with the segments is reached the fingers drop away from the segments, the gravity movement being limited by the screw or pin 39. Where, however, there is only a small amount of current, (say about fifty 95 milliamperes being used,) the arc is so small that a quick break is not necessary, and therefore stationary contacts are used. It will be observed that in this illustration of the device the oscillating contacts are shown 100 on the lower shaft 16, with which connection is made from motor to battery, which in a signal would consume the most current. The other fingers are connected to the same battery, but feed into a high-resistance magnet, 105 (not shown,) which may be a lock-magnet or relay-magnet consuming currents of small quantity. Fingers 24, it will be observed, feed to the same source, though they may be so placed, as shown in Fig. 1, as to cut in at 110 different times with the contact segments or blades 10, while fingers 29 30 feed to different sources, though the position of the segments or blades 10 may be such that one pair of fingers will cut into contact previous to the other 115 pair.
- 120 It will of course be understood that any number of pairs of contact-fingers may be suspended from the studs as may be required by the different movements which are to be made, 125 and a corresponding increase in the segments 10 may be made. One or more pair of the fingers may be insulated, as shown in the present illustration, for the pair of fingers 30 for use in connection with any desired independent circuit. It will also be noted that all circuits are controlled by the rotation of the main shaft, which latter may be driven either electrically or mechanically.

Having fully described my invention, what I claim as new, and desire to secure by Letters Patent, is—

- 5 1. In a circuit-controller, the combination with a supporting-frame, a plate supported by said frame, studs mounted in said plate, contact-fingers arranged in pairs on said studs, and contact-blades movable in the arc of a circle to make and break contact with said fingers.
- 10 2. In a circuit-controller, a supporting-plate, studs mounted in said plate; collars mounted on said studs, a pair of contact-fingers carried by each collar, and contact-blades movable in the arc of a circle between the pairs of fingers to make and break contact therewith.
- 15 3. In a circuit-controller, a segmental supporting-plate, studs mounted in said plate, collars mounted on each of said studs, a pair of contact-fingers mounted in recesses provided therefor in each collar, and contact-blades movable in the arc of a circle between the fingers to make and break contact there-
- 20 25 with, substantially as described.
- 25 4. In a circuit-controller, a supporting-plate, one or more studs mounted in said plate, collars mounted on the stud or studs with their opposite faces recessed, contact-fingers mounted in said recesses, and contact-blades movable between the fingers to make and break contact therewith.
- 30 5. In a circuit-controller, a series of suitably-supported studs, collars mounted on each of said studs, with their opposite faces recessed, and contact-fingers mounted in said recesses for engagement with opposite faces of contact-blades to make and break contact.
- 35 6. In a circuit-controller, a series of suitably-supported studs, collars mounted on said studs, a pair of contact-fingers carried by each of said collars, one pair of said fingers being insulated from the supporting-stud, and contact-blades movable between the fingers, substantially as described.
- 40 7. In a circuit-controller, a series of suitably-supported studs, collars mounted on said studs, a pair of contact-fingers carried by each of said collars, one pair of the fingers 45 having an oscillating movement, and contact-blades movable in the arc of a circle between the fingers.

8. A multiple-circuit controller, comprising a series of electrically-connected spring-fingers arranged in pairs, one pair of fingers 55 being capable of oscillatory movement on their support, and segmental contact-blades movable in the arc of a circle between the pairs of fingers for contact therewith.

9. A multiple-circuit controller comprising 60 a series of suitably-mounted spring contact-fingers one of which is capable of oscillatory movement on its support, and contact-blades movable between the fingers in the arc of a circle for engagement with the fingers. 65

10. In a multiple-circuit controller, a supporting-plate, studs mounted in said plate and insulated therefrom, collars mounted on each of said studs, a pair of spring contact-fingers carried by each of said collars, one of 70 said collars and fingers carried thereby being insulated from their stud, and contact-blades movable in the arc of a circle between the fingers and provided with knife-edges, as and for the purpose described. 75

11. A multiple-circuit controller embodying a support, studs mounted therein and insulated therefrom, collars mounted on said studs, a pair of spring-fingers carried by each of said collars, one of said pairs of fingers 80 capable of oscillatory movement, and contact-blades which are movable between the pairs of fingers to make and break contact therewith.

12. In a circuit-controller, a support, a stud 85 mounted in said support, a collar mounted on said stud to partially rotate thereon, a pair of spring-fingers carried by the collar and movable therewith, means for limiting the movement of said collar and fingers, and 90 a contact-blade movable between the fingers to make and break contact therewith.

13. In a circuit-controller, a support, a stud mounted thereon, collars mounted on said stud, a pair of spring-fingers carried by 95 each of said collars, and contact-blades movable in the arc of a circle between the fingers to make and break contact therewith.

In testimony whereof I affix my signature in the presence of two witnesses.

REINHOLD HERMAN.
